UNITED STATES PATENT OFFICE.

LEON L. KATZENSTEIN, OF WORCESTER, MASSACHUSETTS.

DESIGN FOR A PANEL FOR A LAMP-SHADE.

59,599.

Specification for Design.

Patented Nov. 8, 1921.

Application filed February 17, 1921. Serial No. 445,901. Term of patent 7 years.

To all whom it may concern:

Be it known that I, LEON L. KATZENSTEIN, a citizen of the United States, residing at Worcester, in the county of Worcester and State of Massachusetts, have invented a new and original and ornamental Design for a Panel for a Lamp-Shade, of which the following is a specification; reference is to be had to the accompanying drawing, in which the figure is a front view of a lamp-

shade panel, showing my new design, the trapezoidal opening in the frame exposing a piece of cloth gathered in to form substantially vertical folds.

I claim:—

The ornamental design for a panel for a lamp shade, as shown.

In testimony whereof I have hereunto affixed my signature.

LEON L. KATZENSTEIN.
